6 Claims. (Cl. 298—80)

This invention relates to a process for improving the octane number and other characteristics of petroleum distillates, especially middle distillate fractions, and it is particularly directed to a process wherein the distillate is first fractionated into a number of streams, each of which is then passed with hydrogen at elevated temperatures and pressures over a catalyst having both cracking and hydrogenation activity. In the ensuing reaction, wherein substantial hydrogen is consumed, the distillate fraction of each feed stream is converted to a product boiling below the initial boiling point of said stream.

This application is a continuation-in-part of our application Serial No. 637,328, filed January 30, 1957, now abandoned, which in turn was a continuation-in-part of our application Serial No. 478,784, filed December 30, 1954, now abandoned.

The present invention is based on the discovery that excellent yields of high quality products can be obtained from any one or more of a variety of petroleum distillate fractions boiling in the range from about 175 to 850° F. by a process involving the following interrelated steps. The distillate is first fractionated into at least two and preferably into three or more feed fractions, each having an appreciable boiling range. Thereafter, each of the fractions so obtained, along with at least 1500 s.c.f. of hydrogen per barrel thereof, is passed through an isomerization-cracking zone provided with a catalyst made up of one or more hydrogenating-dehydrogenating components disposed on a support having active cracking characteristics, said zone being maintained at pressures of at least 600 p.s.i.g., and at temperatures between about 400 and 900° F. The space rate utilized may be varied within relatively wide limits, e.g., from 0.1 to 15. The reaction occurring under these conditions results in a substantial net consumption of hydrogen as the feed (including any recycled stock) is converted to the desired high quality product fractions. Said product fractions are recovered from the respective effluent streams from the isomerization-cracking zone, or zones, as the portions boiling essentially below the initial boiling point of the particular naphtha feed fractions concerned and may therefore be termed synthetic products. Said synthetic products have a low content of normal paraffins, and a high content of isoparaffins and ring compounds. They are valuable for low freeze point jet fuel purposes, and are reformable to high octane gasolines in good yield. While good conversions (often exceeding 50%) to said synthetic products can be obtained in single-pass operations, this conversion can be increased to values between 70 and 100% by recycling to the catalyst reaction zone the individual bottoms streams remaining after removal of synthetic products, said recycle being returned to the reaction zone either alone or along with added quantities of the particular feed fraction concerned, added hydrogen being also supplied in either case.

As indicated above, there is a net consumption of hydrogen, normally amounting to from 800 to 3000 s.c.f. of hydrogen per barrel of feed converted in the isomerization-cracking zone. In this connection, conversion is arbitrarily expressed in terms of the amount of feed (including recycled effluent bottoms) converted to product

2

boiling below the initial boiling point of said feed stocks. This hydrogen deficiency can be met in any desired fashion. Further, the reactions taking place in the isomerization-cracking zone entail a net reduction in the aromatic content of the stock as measured by comparing the aromatic content of the feed (including recycle) with that of the synthetic product portion of the effluent from the said reaction zone. Despite this reduction in aromatic content, however, the octane number of synthetic gasoline product is well above that of the corresponding feed fraction, and the product is reformable in good yield to a high octane gasoline product. Moreover, the yield of said product is extremely high, and normally ranges from about 80 to 110 volume percent in terms of the volume of (liquid) fresh feed supplied to the isomerization-cracking zone. From this it is obvious that the process is an extremely efficient one entailing little degradation of the feed to less valuable, normally gaseous components.

When, contrary to the method described above, a naphtha feed stream of relatively wide boiling range (e.g., 150° F. or more) is not divided into relatively narrow-boiling fractions for separate processing, but is fed whole to the isomerization-cracking zone, it is not possible to recover more than a small percentage of the synthetic product present in the effluent from said zone, i.e., that boiling below the initial boiling point of the feed. The rest of the synthetic product boils in the same range as portions of the remaining, unconverted feed and thus cannot be separated therefrom. Accordingly, if all the feed is to be converted to synthetic product in such method of operation, it is necessary to further convert already-formed synthetic product to still lower-boiling product fractions, and this represents an entirely uneconomic method.

As feed to be fractionated and catalytically converted in accordance with the process of the present invention, there can be employed any thermally cracked, catalytically cracked or straight run naphtha or gas oil fractions boiling in the range of from about 175 to 850° F., preferably 175 to 650° F., and having a boiling range or spread, of at least 100° F. In addition to possessing the desired boiling point range characteristics, the feed stocks employed in this invention should be low in nitrogen content and preferably should contain less than 200 p.p.m. nitrogen, and more preferably less than 50 p.p.m. This specification is somewhat flexible since higher nitrogen contents can be tolerated with the higher boiling fractions than with the lighter portions of the feed. In the case of stocks which are not already sufficiently low in nitrogen, acceptable levels can be reached by pretreating the distillate (either before or after fractionating the same in the manner described herein) with hydrogen in the presence of a suitable catalyst, for example cobalt- and molybdenum-containing alumina catalyst at elevated temperatures and pressures. A particularly effective catalyst for this purpose is one wherein a coprecipitate molybdenum-alumina material, as prepared in accordance with the disclosure of U.S. Patent No. 2,432,286 to Claussen et al., is combined with cobalt oxide, the final catalyst having a metals content of about 2% cobalt and 7% molybdenum. Representative processing conditions for removing nitrogen with this catalyst are 600–800° F., 500–2000 p.s.i.g., and 1000–6000 standard cubic feet of hydrogen per barrel of feed stock.

As noted above, the feed stock employed should be fractionated into at least two and preferably into three or more fractions, each having an appreciable boiling range. Normally, this range or spread, will be of the order of 50 to 125° F., with the number of fractions employed being such that all portions of the given feed stock fall into one fraction or another. In the case of stocks boiling in major portion within the range of from

about 270 to 450° F., at least one fraction should be chosen so as to contain the C₈ aromatics and other components boiling somewhat below the C₉ aromatics present (a suitable cut, for example, being one boiling from about 270 to 320° F. $\pm$ about 10°), while another fraction should be selected so as to contain the C₉ aromatics together with other hydrocarbons present normally boiling between about 320 and 370° F., again $\pm$ about 10°. Additionally, one or more other fractions may be obtained boiling above the latter fraction, as is also the case with the portion of the feed, if any, boiling below 270° F.

The catalyst employed in the isomerization-cracking zone is one wherein a material having hydrogenating-dehydrogenating activity is deposited or otherwise disposed on an active cracking catalyst support. The cracking component may comprise any one or more of such acidic materials as silica-alumina, silica-magnesia, silica-alumina-zirconia composites, alumina-boria, fluorided composites, and the like, as well as various acid treated clays and similar materials. The hydrogenating-dehydrogenating components of the catalyst can be selected from any one or more of the various Groups V, VI, VII and VIII metals, as well as from the oxides and sulfides thereof, alone or together with promoters or stabilizers that may have by themselves small catalytic effect, representative materials being oxides and sulfides of molybdenum, tungsten, vanadium, chromium and the like, as well as of metals such as iron, nickel, cobalt and platinum. If desired, more than one hydrogenating-dehydrogenating component can be present, and good results have been obtained with catalysts containing composites of two or more of the oxides of molybdenum, cobalt, nickel, chromium and zinc, and with mixtures of said oxides with fluorine. The amount of the hydrogenating-dehydrogenating component present can be varied within relatively wide limits of from 0.5 to 30%, preferably 0.5 to 15%, based on the weight of the entire catalyst. Within these limits, the amount of said component present should be sufficient to provide a reasonable catalyst on-stream period at required conversion levels, but insufficient to effect substantial saturation of any except highly substituted and polynuclear aromatic rings under the reaction conditions employed in the isomerization-cracking zone.

Having selected or prepared the low nitrogen feed stock to be processed, and split the same into the desired portions, the process of the present invention can be carried out in a continuous fashion by preheating the feed and added hydrogen supplied therewith to the extent necessary to bring the reaction in the isomerization-cracking zone on-stream at the desired temperature about 400° F. Thereafter, while maintaining pressures and feed throughput rates at the desired levels, the temperature in said zone is controlled so as to maintain (average) reaction temperatures therein at optimum levels. The normal procedure is to raise such temperatures as the reaction progresses in order to maintain adequate per-pass conversion levels. Following the on-stream period the reaction unit may be switched to the regeneration portion of the cycle if desired. While the length of the on-stream period will vary from stock to stock, the isomerization-cracking catalyst will remain active for periods of from about 75 to 500 or more hours under favorable operating conditions. Catalyst activity can then be restored by a conventional regeneration practice involving the burning of contaminants with an O₂-containing gas.

The foregoing remarks presupposed the employment of a fixed bed method of operation, and the same is preferred. However, the process of this invention can also be practiced using a moving catalyst bed or one of the fluidized type where catalyst regeneration is continuous and on-stream periods can be indefinitely prolonged.

In the case of each feed fraction, the effluent from the isomerization-cracking zone is freed of a hydrogen-rich stream (normally recycled to said zone) and of other normally gaseous components, with the remainder then

being passed to a fractionation zone for recovery of the desired (normally synthetic) product fraction or fractions. The remaining, higher-boiling material, in the case of each effluent stream, can then be withdrawn in whole or part from the system if desired (for use as a component of various gasoline, jet or diesel fuels) though it preferably is recycled to the isomerization-cracking zone for further conversion therein, along with added fresh feed and hydrogen. The synthetic gasoline product fractions recovered from the various effluent streams can be combined, if desired, to produce a high octane gasoline of full boiling range, or they may be separately employed in any desired fashion, usually as premium blending stocks.

A process flow for a specific embodiment of this invention is illustrated in the appended drawing, and a detailed description of a preferred manner of operation will be discussed below in connection with that drawing.

A distillate feed stream (for example one having a boiling point range of 230 to 380° F.) is passed through line 10 into a fractionating column 11 which separates the naphtha into a light fraction boiling between about 230 and 280° F. which is taken overhead through line 13, an intermediate fraction boiling between about 280 and 330° F. taken through line 14, and the bottoms fraction boiling between 330 and 380° F. withdrawn through line 15. The fraction in line 13, along with hydrogen supplied through line 16, is heated to reaction temperature by passage through a heat exchanger 17, the heated admixture so produced then being passed into reaction zone 18 where it is contacted with a clay-type cracking catalyst incorporating molybdenum oxide as the hydrogenation catalyst. The effluent from this reaction zone is passed via line 19 through a condenser 20 and into a gas-liquid separator 21. Hydrogen, along with a small percentage of other gaseous components, is withdrawn from separator 21 and returned through line 22 to the hydrogen supply line 16, while the liquid condensate in the separator is withdrawn through line 23 and passed into distillation zone 25 for recovery of products. Normally gaseous materials are removed from zone 25 through line 27, while a gasoline fraction boiling below the initial boiling point (230° F.) of the feed fraction in line 13 is recovered through line 28. The bottoms from zone 25 are recovered through line 29 and are returned to line 13 for repeated catalytic conversion in zone 18.

The processing of the feed fractions in lines 14 and 15 is similar to that of the fraction in line 13 as described above, said feeds passing, along with hydrogen supplied through lines 30 and 31, through heat exchangers 32 and 33 to reaction zones 34 and 35 provided with catalyst of similar nature to that present in zone 18. The respective effluent streams from the latter reaction zones are passed via lines 36 and 37 through condensers 38 and 39 to gas-liquid separators 40 and 41 from which hydrogen is taken overhead through lines 42 and 43 and returned to the respective hydrogen supply lines 30 and 31. The liquid condensate streams from the separators are withdrawn through lines 44 and 45 and passed into respective distillation zones 46 and 47, provided with lines 48 and 49 for release of normally gaseous materials. From the zone 46 a gasoline fraction boiling below 280° F. is taken through line 50 and joined with that from line 28, while from zone 47 a gasoline stream boiling below 330° F. is taken through line 51 and also joined with that from line 28, the combined stream in line 52 representing the high quality product which, after suitable debutanizing and other steps, if required, is ready for use as a premium gasoline having a relatively wide boiling range. The bottoms from the zones 46 and 47 are taken through lines 53 and 54 and are recycled back to lines 14 and 15, respectively.

In the flow diagram, various of the required pumps, heat exchangers, valves, recycle systems and other items of flow control equipment have been omitted in the interest of simplicity and clarity of expression, the placing

of such equipment being evident to those skilled in the art once the general procedure has been outlined. The process of the invention is illustrated by the following examples.

EXAMPLE 1

In this operation there was employed a naphtha having the following inspections:

A.P.I. gravity	48.1
Aniline point	° F. 108
Volume percent aromatics	23
Volume percent paraffins plus naphthenes	76
F-1 clear octane number	60.8

For the purpose of this example, a total of 8 volume percent constituting the fractions boiling below 180° F. and above 430° F. was removed from the above naphtha by rerunning. The remainder, boiling between 180 and 430° F., and having an aromatic content of 23% by volume, was distilled with good fractionation into five fractions, as follows:

Fraction	Boiling Range, ° F.	Volume percent of Whole Naphtha	30
1	180 to 230	13.1	
2	230 to 280	21.3	
3	280 to 330	24.4	
4	330 to 380	20.6	
5	380 to 430	12.6	
		92.0	

Each of the foregoing fractions was then passed at a rate of 2 v.v./hr., at 800° F. and 1200 p.s.i.g., along with 6000 standard cubic feet of hydrogen per barrel of feed, through a catalyst comprised of molybdenum oxide (1% Mo) deposited on a silica-alumina cracking catalyst. Each conversion stream was then fractionated so as to recover the product fraction boiling below the initial boiling point of the particular naphtha cut involved, with the bottoms then being recycled back through the reaction zone, along with added feed and fresh as well as recycle hydrogen. Each of the lower boiling (gasoline) fractions thus recovered was then freed of C₄ and lighter components, the yield and quality of each resulting, debutanized product portion produced being indicated below in Table I.

Table I

Yield, Volume percent based on Feed Fraction of Debutanized, Synthetic Product		F-1 Clear Octane Number of Synthetic Debutanized Product	Hydrogen Consumption (s.c.f.) per Barrel of Feed Converted to Synthetic Product
Feed Fraction	Single Pass	Extinction Recycle	
180-230° F.	6.1	39.4	86 900
230-280° F.	16.9	53.8	86 1,280
280-330° F.	30.3	77.6	87 1,200
330-380° F.	45.5	84.2	90 1,100
380-430° F.	53.1	90.6	90.5 1,350

¹ Product boiling below initial boiling point of feed fraction.

The blend obtained on combining the synthetic, debutanized products obtained from the above operation has an aromatic content of 20 volume percent which compares with an aromatic content of 23 volume percent in the entire 180 to 430° F. naphtha feed. The final yield of C₅-380° F. gasoline produced (all as synthetic product) is equivalent to 70 volume percent, while the C₄-380° F. yield is equivalent to 102.7 volume percent, both in terms of the volume of 180-430° F. naphtha feed. The overall F-1 clear octane number of the C₅-380° F. synthetic product is 88.2.

When, under the same conditions of temperature, pressure, throughput rate, hydrogen/feed ratio and catalyst, the whole (180-430° F.) fraction is processed in the

fashion described above it is found that the F-1 clear octane rating of the whole effluent, on a once through basis, is raised from a value of approximately 60 to 69.0. By fractionating this whole naphtha effluent, it is not possible to recover more than about 14 volume percent of a debutanized synthetic gasoline product (having an F-1 clear octane rating of 88), and this product is undesirable since its end point is low (about 180° F.). The yield of gasoline above 80 F-1 clear octane number is below 25 volume percent. These yields are in contrast with that of 70% to a gasoline of full boiling range and 88.2 F-1 clear octane number, as obtained in the selective operation described above upon which the present invention is based.

EXAMPLE 2

15 A cycle oil boiling in the range 400 to 850° F. is separated into two fractions, a light fraction boiling from 400 to 525° F. and a heavy fraction boiling from 525 to 850° F. The light fraction is separately hydrocracked in a first conversion zone over a catalyst comprising nickel sulfide on silica-alumina at a space velocity of 2 v.v./hr., a temperature of 700 to 800° F., and a pressure of 1300 p.s.i.g., in the presence of 6000 standard cubic feet of hydrogen per barrel of feed. The heavy fraction also is 20 separately hydrocracked, in a second conversion zone, over the same type of catalyst and under the same conditions as used in the first conversion zone. The yields from each of the two hydrocracking zones are as follows:

	Light Feed	Heavy Feed	Total
Weight Percent			
35 C ₃ -	3.5	1.4	4.9
iC ₄ -	6.7	4.0	10.7
nC ₄ -	3.6	1.7	5.3
Volume Percent			
40 C ₅ -400° F.	102	85	187
400-525° F.		20	20

45 The effluent from the first conversion zone is separated into a gasoline product fraction and a fraction boiling in the range 400 to 525° F. which is recycled to the first conversion zone.

50 The effluent from the second conversion zone is separated into a gasoline product fraction, a middle distillate fraction boiling from 400 to 525° F., and a fraction boiling above 525° F. which is recycled to the second conversion zone.

55 The middle distillate fraction recovered as a product from the second conversion zone is highly useful for jet fuel purposes, particularly because of its low freeze point. The first crystal point of the product is below -70° F.

56 If the entire original 400 to 850° F. feed stock is not separated as aforesaid into a lighter and a heavier portion which are separately hydrocracked, but rather is hydrocracked in toto in a single conversion zone, the 400 to 525° F. middle distillate product has a considerably higher freezing point, because it contains unconverted light cycle oil which has a first crystal point of about 0° F. I.e., the 400 to 525° F. material recycled to the first conversion zone above has a first crystal point of about 0° F. and if even a small amount of this material is mixed with the 400 to 525° F. middle distillate product from the second conversion zone, the freeze point of that product would be raised in an intolerable amount, perhaps as much as 50° F.

60 We claim:

1. A process for upgrading a petroleum distillate boiling in the range of from about 175 to 850° F. and having a boiling range of at least 100° F., which comprises fractionating said distillate to separate the same into at least two feed fractions each having an appreciable boiling

range; separately passing each of said feed fractions, along with at least 1500 s.c.f. of hydrogen per barrel thereof, in contact with a catalyst comprising at least one hydrogenating-dehydrogenating component and an active cracking catalyst support in an isomerization-cracking zone for a given on-stream period, said zone being maintained at a pressure of at least 600 p.s.i.g. and at an average temperature between about 400 and 900° F., and recovering from the effluent from said isomerization-cracking zone, as a product of the conversion reaction occurring therein, a product fraction boiling essentially below the initial boiling point of the particular feed fraction employed; said conversion reaction being accompanied by a net consumption of from about 800 to 3000 s.c.f. of hydrogen per barrel of feed converted to synthetic product in said zone.

2. The process of claim 1, wherein the portions of said effluent boiling above the end point of said recovered product fraction are recycled, at least in part, to said isomerization-cracking zone.

3. A process for upgrading a petroleum naphtha boiling in a range of from about 175 to 850° F. and having a boiling range of at least 100° F., which comprises fractionally distilling said naphtha to separate the same into at least two feed fractions, each having an appreciable boiling range, separately contacting each of said fractions, in the presence of at least 1500 s.c.f. of hydrogen per barrel thereof, at pressures above 600 p.s.i.g., and at temperatures between about 400 and 900° F., with a catalyst comprised of at least one hydrogenating-dehydrogenating component and an active cracking catalyst support; separating the hydrogen and other normally gaseous components from each of the resulting reaction product streams; and fractionally distilling the remainder

of each of said streams into a bottoms fraction and an overhead product fraction boiling essentially below the initial boiling point of the feed fraction involved; said process being characterized by a net consumption of 5 from about 800 to 3000 s.c.f. of hydrogen for each barrel of feed converted to synthetic product by said contact with the catalyst.

10 4. The process of claim 3, wherein a hydrogen-rich gas separated from said reaction product streams is recycled back through the catalyst along with added hydrogen, and wherein said bottoms fraction is also recycled back through the catalyst along with added quantities of the corresponding feed fraction from which said bottoms fraction derives.

15 5. The process of claim 4, wherein said feed fractions each have a boiling range of from about 50 to 150° F.

6. The process of claim 4, wherein said petroleum naphtha is one which boils in major portions within the range of from about 270 to 450° F., with a boiling range 20 of at least 150° F., and which is fractionated into at least two fractions, one of which contains C₈ aromatics and boils in the range of from about 270 to 320° F., ± about 10°, and another of which contains C₉ aromatics and boils in the range of from about 320 to 370° F., 25 ± about 10° F.
